UNITED STATES PATENT OFFICE.

CLARENCE SNOWDEN, OF CINCINNATI, ASSIGNOR OF ONE-HALF TO THOMAS JEFFERSON SMITH, OF COVINGTON, OHIO.

UMBRELLA ATTACHMENT FOR BICYCLES.

SPECIFICATION forming part of Letters Patent No. 380,059, dated March 27, 1888.

Application filed August 4, 1887. Serial No. 246,161. (No model.)

To all whom it may concern:

Be it known that I, CLARENCE SNOWDEN, a resident of Cincinnati, county of Hamilton, and State of Ohio, have invented certain new and useful Improvements in Umbrella-Attachments for Bicycles, of which the following is a specification.

The several features of my invention and the advantages arising from their use con- 10 jointly, or otherwise, will be apparent from the following description.

In the accompanying drawings, forming part of this specification, Figure 1 is a perspective view of a bicycle provided with my 15 improvements. Fig. 2 is a vertical central section of the rod supporting the umbrella. Fig. 3 illustrates the relation of the umbrella-rope to the supporting-pulley. Fig. 4 is a detailed view of the clamp holding the supporting-rod, 20 part being shown in section. Fig. 5 illustrates the position of the clamp when the umbrella is not attached.

To each side of the yoke A of the bicycle one arm, B, of the rod-support is attached. 25 Each arm B is hinged to a plate, b, which is firmly attached to the yoke A. The hinge b' is set at a suitable angle, preferably of about ninety degrees, on the plate b, so that when the arm B is swung backward it lies against 30 the face of the yoke, as shown in Fig. 5. The outer end of each arm B is provided with a half-circle, which, with its fellow of the other arm B, forms the socket C, which is screw-threaded, and into which the rod D is screwed. 35 To insure the proper adjustment of the parts of the socket C, one half is provided with a little pin, b², which is received into a corresponding socket in the other half. The bar B' is provided with right and left hand screw- 40 threads and is screwed into the arms B with the effect of either separating them or of clamping them together. A screw, b³, may also be used to assist in holding the arms B together.

The function of the arms B is to form a support for the rod D, and while the form shown 45 in the drawings is preferred, it is evident that other forms of support projecting in front of the bicycle will perform the same function. The rod D is preferably made in several sec- 50 tions telescoped together and provided with

suitable clamp-screws for holding them in position. The top of the rod D is curved over the bicycle.

The umbrella E is hung by means of a cord, F, which extends from side to side of the umbrella and passes once around the pulley G, which latter is suspended in the open strap G', suspended from the rod D. Suitable stay-cords, f, are employed to steady the umbrella. The top of the umbrella is preferably provided 6c with the opening e for the escape of wind.

To give additional support to the rod D, rigid guy-rods H are employed. These rods extend from the rod D to the guiding-bar of the bicycle. They are provided with adjust- 65 ing turn-buckles h. When the umbrella is removed, the arms B may be allowed to remain projecting in front of the bicycle, but are preferably dropped to the sides of the yoke.

The edge of the umbrella E is provided with 70 the fringe J, each thread of which is weighted with a leaden pellet or other suitable weight, j. The object of the weighted fringe is to act as a ballast.

What I claim as new, and desire to secure by 75 Letters Patent, is—

1. In combination with a bicycle, a forwardly-projecting support, rod D, and umbrella suspended therefrom, substantially as and for the purposes specified. 80

2. In combination with a bicycle, arms B, attached to the yoke of the bicycle, rod D, and umbrella suspended therefrom, substantially as and for the purposes specified.

3. In combination with a bicycle, the arms 85 B, hinged at an angle to the yoke A, and clamp for holding them together, substantially as and for the purposes specified.

4. In combination with a bicycle, the sup- 90 port B B, telescoped rod D, and umbrella E, substantially as and for the purposes specified.

5. In combination with a bicycle, the sup- 95 port B B, rod D, and umbrella E, provided with weighted fringe, substantially as and for the purposes specified.

6. In combination with a bicycle, the sup- 100 port B B, rod D, and umbrella E, provided with opening e, substantially as and for the purposes specified.

7. In combination with a bicycle, supports

B B, rod D, provided with stay-rods H, and umbrella supported from rod D, substantially as and for the purposes specified.

8. In combination with a bicycle, an umbrella with its supporting-rod suitably upheld, said supporting-rod having three stay-rods, one attached to upper part of spindle, the other two attached to the guiding-bar, substantially as and for the purposes specified.

9. In combination with a bicycle, umbrella, to supporting-rod therefor, said supporting-rod suitably upheld, and provided with stay-rods adjustable in length, substantially as and for the purposes specified.

CLARENCE SNOWDEN.
